Inventor.

UNITED STATES PATENT OFFICE.

ROBERT E. BELL, OF DETROIT, MICHIGAN.

DESIGN FOR A BOTTLE.

50,011.

Specification for Design.

Patented Dec. 12, 1916.

Application filed October 13, 1916. Serial No. 125,518. Term of patent 14 years.

To all whom it may concern:

Be it known that I, ROBERT E. BELL, a citizen of the United States, residing at Detroit, in the county of Wayne and State of Michigan, have invented a new, original, and ornamental Design for Bottles, of which the following is a specification, reference being had to the accompanying drawing, forming part thereof.

The figure is a perspective view of a bottle, showing my new design.

I claim:

The ornamental design for a bottle, as shown.

ROBERT E. BELL.
